DESIGN FOR AN AIRCRAFT ENGINE STARTER SUPPORTING FRAME

David J. Conant, Shaker Heights, Ohio, assignor
to Jack & Heintz Research Corporation, Bed-
ford, Ohio, a corporation of Ohio

Application January 24, 1944, Serial No. 112,306

Term of patent 14 years

(Cl. D71—1)

To all whom it may concern:

Be it known that I, David J. Conant, a citizen
of the United States, residing at Shaker Heights,
in the county of Cuyahoga and State of Ohio,
have invented a new, original, and ornamental
Design for an Aircraft Engine Starter Support-
ing Frame, of which the following is a specifica-
tion, reference being had to the accompanying
drawing, forming part thereof, wherein:

Figure 1 is a perspective view of an aircraft
engine starter supporting frame showing my new
design; and

Figure 2 is a top plan view.

I claim:

The ornamental design for an aircraft engine
starter supporting frame, substantially as shown.

DAVID J. CONANT.
